UNITED STATES PATENT OFFICE.

LEWIS F. BUTMAN, OF RANDOLPH, AND CHANCY E. BIXBY, OF BARRE, VERMONT.

MILK COOLER AND STRAINER.

1,346,937.

Specification of Letters Patent. Patented July 20, 1920.

Application filed August 22, 1919. Serial No. 319,200.

To all whom it may concern:

Be it known that we, LEWIS F. BUTMAN and CHANCY E. BIXBY, citizens of the United States, residing at Randolph and Barre, respectively, in the counties of Orange and Washington, respectively, and State of Vermont, have invented certain new and useful Improvements in Milk Coolers and Strainers, of which the following is a specification, reference being had to the accompanying drawings.

This invention relates to devices for treating milk, and particularly to a means for cooling milk as it is placed in cans and straining the milk.

The general object of our invention is to provide a very simple construction for this purpose which embodies a cylindrical ice container adapted to be inserted in a milk can, and a cap closing the ice container and supporting an annular strainer, a funnel, and means for directing milk in a film against the ice container.

A further object is to provide means for bracing the strainer from the ice container, said means also providing for the support of the device properly centered within the mouth of a milk can.

Other objects will appear in the course of the following description.

Our invention is illustrated in the accompanying drawings, wherein:—

Figure 1 is a vertical sectional view of our milk cooler and strainer showing in dotted lines the application of the device to a can of milk;

Fig. 2 is a top plan view of the milk cooler and strainer.

Referring to these drawings, it will be seen that this cooler and strainer comprises a cylindrical ice receptacle 10, closed at its bottom, open at its top, and of a length sufficient, preferably, so that the bottom of the receptacle will rest upon the bottom of the metallic can A. Adapted to close the top of the ice receptacle is a conical cap 11 having a depending flange fitting snugly over the ice receptacle, and attached to the margin of this cap and extending horizontally outward therefrom is an annular strainer of wire gauze, designated 12, and having a diameter slightly less than the diameter of the mouth of the can. Extending upward from the margin of the wire gauze is an upwardly flaring hopper-shaped receiver or funnel 13. Connecting the lower

edge of this funnel with the flange 14 of the cap are the upwardly and outwardly extending braces 15 which may be made of light wire.

Coacting with the strainer and member 13 is means for directing the milk passing through the strainer against the upper end of the ice container 10 so that the milk will flow down this ice container in the form of a thin film and thus be more thoroughly cooled than it otherwise would be. To this end, the lower end of the member 13 is provided with a downwardly extending, annular flange 16; and fitting this flange snugly is an annular member 17 having a downwardly and centrally inclined, annular bottom 18 which, when the member is in place, terminates at a relatively small distance from the ice container 10. This member acts to deflect the milk passing through the strainer 12 against the wall of the ice container. Preferably, the upper edge of the member 17 is outwardly beaded, as at 19, so as to prevent the member 17 from slipping downward into the can A under any circumstances. It will be seen that the proportions of this device are such that the member 17 fits snugly within the neck of the milk can A, the strainer fits snugly into the member 17 with its cap 11 over the top of the ice container, and the ice container rests on the bottom of the can in the manner illustrated in Fig. 1.

In the operation of this device, the ice container is filled with ice and then the cap 11 is disposed thereon and the ice container inserted within the metallic can A so as to rest upon the bottom thereof with the funnel or receiver 13 disposed to project into the mouth of the metallic can. Milk is then poured into the receiver and passes downward through the wire gauze into the milk can. The milk or other liquid is caused to run down the periphery of the cooler 10 in small streams or thin films so that the milk is readily cooled by the salt and ice within the container 10. This device is left in the can until the milk is cooled to the temperature desired, when it may be withdrawn and refilled and disposed in another can. The device is very simple and is thoroughly practical. It forms a convenient means for simultaneously straining and cooling milk or other liquids.

While we have illustrated a form of our invention which is extremely simple and

which has been found thoroughly effective in use, yet we do not wish to be limited thereto, as many minor modifications might be made therein without departing from the spirit of the invention as defined in the appended claims.

We claim:—

1. A device of the character described comprising an ice receptacle adapted to be disposed within a milk can and having a removable cap at its upper end, an annular receiver surrounding the cap and projecting above it, a wire gauze strainer attached to the lower edge of the receiver and extending to the cap, the receiver having an annular flange extending downward below the strainer, and an annular member formed to fit snugly upon the exterior of the last named flange and having a portion extending downward and inward from the ice receptacle but spaced slightly therefrom when in operative position.
2. A device of the character described comprising an ice receptacle adapted to be disposed within a milk can and having a removable cap at its upper end, an annular receiver surrounding the cap and projecting above it, a wire gauze strainer attached to the lower edge of the receiver and extending to the cap, the receiver having an annular

flange extending downward below the strainer, and an annular member formed to fit snugly upon the exterior of the last named flange and having a portion extending downward and inward from the ice receptacle but spaced slightly therefrom when in operative position, the upper edge of the annular member being outwardly turned and beaded.

3. A device of the character described comprising an ice receptacle adapted to be disposed within a milk can and having a movable cap at its upper end, an annular receiver mounted upon and surrounding the cap and projecting above it, a strainer attached to the lower edge of the receiver and extending to the cap, and a deflector formed to detachably engage the lower portion of the receiver and having a portion disposed below the strainer and extending downward and inward from the receiver into a position adjacent to but spaced slightly from the ice receptacle to thereby deflect the milk discharged from the receiver into contact with the wall of the ice receptacle.

In testimony whereof we hereunto affix our signatures.

LEWIS F. BUTMAN.
CHANCY E. BIXBY.
